United States Patent

Des. 240,449

Patented July 6, 1976

240,449

FLASHLIGHT

Howard T. Livingston, 700 Leisure Drive 32,
Fort Worth, Tex. 76112

Filed May 14, 1975, Ser. No. 577,302

Term of patent 14 years

Int. Cl. D26—02

U.S. Cl. D48—24 A

FIG. 1 is a front elevational view of a flashlight showing my design;

FIG. 2 is a side elevational view of the flashlight;

FIG. 3 is a top view of the flashlight shown in FIG. 1;

FIG. 4 is a bottom view of the flashlight shown in FIG. 1;

FIG. 5 is an enlarged cross-sectional view taken on line V—V of FIG. 1;

FIG. 6 is an edge view of the flashlight taken from line VI—VI in FIG. 1.

I claim:

The ornamental design for a flashlight, as shown and described.
